RAIL ANCHOR

Robert Andrew Thomann, Clayton, Mo., and Jacob Alvin Hyle, Detroit, Mich., assignors, by mesne assignments, of fifteen per cent to Forbes National Bank, Pittsburgh, Pa., a corporation of Pennsylvania

Application January 29, 1943, Serial No. 473,988

3 Claims. (Cl. 238—327)

This invention relates to rail anchors, and is an improvement over the rail anchors disclosed in Thomann's Patent Number 2,268,327, dated December 30, 1941, and his co-pending application, Serial Number 451,053, filed July 15, 1942.

An object of this invention is to provide a rail anchor which is formed with a base, a pair of clamping jaws, and an offset depending abutment or wing engageable with the cross tie below the tie plate.

Another object of this invention is to provide a rail anchor provided with a base, clamping jaws, a depending wing or abutment engageable with one side of a cross tie, and a laterally extending lug formed on the outer portion of the base for engagement with the base flange of the rail to hold the anchor against tilting or rocking.

With the foregoing objects in view, and others which may hereinafter appear, the invention consists of the novel construction, combination and arrangement of parts, as will be more specifically referred to and illustrated in the accompanying drawing wherein is illustrated an embodiment of the invention, but it is to be understood that changes, modifications and variations may be resorted to which fall within the scope of the invention as claimed.

Figure 1 is a vertical section through a rail having an anchor constructed according to an embodiment of this invention mounted thereon;

Figure 2 is a fragmentary sectional view taken on the line 2—2 of Figure 1;

Figure 3 is a detail side elevation of the anchor removed from the rail.

Referring to the drawing, the numeral 10 designates generally a rail provided with a base flange 11, which is mounted on a tie plate 12. The tie plate 12 is secured in a conventional manner to the upper side of a cross tie 13.

In order to provide means for anchoring the rail 10 with respect to the cross tie 13, we have provided a rail anchor which includes an elongated base portion or body 14. The body 14 is adapted to be disposed below the base flange 11, and is also adapted to extend below the tie plate 12. The base 14, at one end thereof, has formed integral therewith, a C-clamp, generally designated as 15. The C-clamp 15 includes a lower jaw 16 which is adapted to engage the lower side of the base flange 11.

An upper resilient jaw 17 is formed integral with the lower clamping jaw 16, and is connected to the lower jaw 16 by means of an arcuate connecting member 18. The opposite sides of the clamping jaw 17, and the connecting member 18, 55

are provided with grooves 19 in order to reduce the amount of metal necessary to construct the jaw member 15. The jaw member 17, on its lower side, is provided with a rail flange engaging face 20 which is inclined inwardly and upwardly with respect to the rail 10, so that in applying the anchor to the rail 10, the jaw 15 is adapted to be struck with a hammer or other tool and the rail engaging face 20 of the jaw 17 is adapted to ride upwardly over the inclined upper side of the base flange 11 and to tension the jaw 15 on the base flange 11.

The base 14, at the end thereof opposite from the jaw 15, has formed integral therewith a second clamping jaw 21. The jaw 21 is adapted to engage the edge or side of the base flange 11, opposite from the jaw 15 when the anchor is in applied position. The jaw 21 is connected with the base 14 by means of a resilient connecting arm 22 which rises upwardly from the base 14, and is provided at its upper outer portion with a flat face 23 engageable against the lower horizontal side 24 of the rail flange 11.

In Figure 3 it will be noted that the upper side 23 of the resilient arm 22 is in a horizontal plane, above the horizontal plane of the upper side of the jaw 15. With a construction of this kind when the jaw 15 is in applied position the arm 22 will be under tension so as to thereby retain the clamping jaw 21 in a clamping position against the opposite edge of the rail flange or base 11.

The base 14 of the rail anchor is maintained in laterally offset position with respect to the adjacent side of the cross tie 13, by means of an inwardly projecting depending wing or plate 25. The wing 25, as shown in Figure 2, is of downwardly tapering configuration, being provided with a vertical inner side 26 and a downwardly 40 and inwardly convergent outer side 27. This wing 25 is adapted to maintain the base 14 in laterally spaced relation with respect to the tie plate 12, and the cross tie 13. By providing a thin, downwardly tapering wing 25, the wing will serve as a cutting blade for cutting the frozen ground or roadbed under traffic conditions or under expansion and contraction of the rail.

In order to provide a means whereby the anchor is held against tilting or rocking in a direction lengthwise of the rail 10, under traffic or other conditions, we have provided a laterally projecting lug 28 which is formed integral with the outer side of the jaw 16. The lug 28 is provided with a flat upper side 29, co-planar with the upper side of the jaw 16 so that the lug 28 will con-

tact at its upper side with the horizontal lower side 24 of the rail base 11.

In the use and operation of this anchor, the device is applied to the rail by movement to the left, as viewed in Figure 1. The clamping jaw 21 is adapted to be engaged beneath the lower horizontal side 24 of the base flange 11, and the jaw 15 is struck with a hammer or other tool so as to forcibly move the jaw 15 inwardly to the adjacent side of the rail flange 11. When the anchor is in fully applied position the jaw 21 will assume the position shown in Figure 1, and the resilient arm 22 connecting the jaw 21 with the base 14 will be under a tension so that the anchor will be locked on the rail 10. In applied position the vertical side 26 of the depending wing 25 will engage against the adjacent vertical side of the cross tie 13. The wing 25 will prevent the base 14 and the clamping jaws 15 and 21 from contacting with the tie plate 12, and the laterally projecting lug 28 will hold the anchor against tilting or rocking in a direction lengthwise of the rail 10.

The anchor herein described is adapted to be made out of any suitable metal by forging, and is preferably constructed out of steel having a high carbon content thus providing the desired inherent resiliency to the anchor.

We claim:

1. A rail anchor comprising an elongated base for positioning beneath the base flange of a rail, an upwardly extending C-clamp formed integral with one end of the base and engageable over one edge of the base flange, a second clamp for engagement with the opposite edge of the base flange, a resilient arm shorter in length than said base connecting said second clamp with the opposite end of the base, said arm being upwardly inclined from the base, and a laterally projecting lug carried by the lower jaw of said C-clamp on the side thereof opposite from the rail tie and

engageable with the lower side of said base flange for holding the anchor against tilting or rocking, and a depending wing carried by said base and offset inwardly therefrom to thereby hold said clamps and said base in laterally spaced relation with respect to a rail tie plate said wing having a relatively wide and flat inner side for contact with the adjacent face of a rail tie.

2. A rail anchor comprising an elongated base for positioning beneath the base flange of a rail, an upwardly extending C-clamp formed integral with one end of the base and engageable over one edge of the base flange, a second clamp for engagement with the opposite edge of the base flange, a resilient arm shorter in length than said base connecting said second clamp with the opposite end of the base, said arm being upwardly inclined from the base, a laterally projecting lug carried by the lower jaw of said C-clamp on the side thereof opposite from the rail tie and engageable with the lower side of said base flange for holding the anchor against tilting or rocking, a depending wing carried by said base and offset inwardly therefrom to thereby hold said clamps and said base in laterally spaced relation with respect to a rail tie plate, said wing having a vertical relatively wide and flat inner side and a downwardly and inwardly inclined outer side thereby forming a ballast cutting blade.

3. A rail anchor comprising a base for positioning beneath the base flange of a rail, a pair of clamping members carried by said base, and means holding the anchor against tilting, said means extending laterally of one of said members and engaging the lower horizontal side of the base flange, said means formed integral with one of said clamping members on the side thereof opposite from the rail tie, and engageable with one face of the base flange.
